ILLUMINATION APPARATUS

Ralph E. Marbury, Wilkinsburg, Pa., assignor to
Westinghouse Electric & Manufacturing Com-
pany, a corporation of Pennsylvania

Application July 17, 1931. Serial No. 551,384

7 Claims. (Cl. 240—1.2)

My invention relates to illumination apparatus and particularly to illumination apparatus for marking obstructions dangerous to air traffic, such as high buildings, transmission towers and the like.

It is an object of my invention to provide a marker light for obstructions to air traffic which will appear as a ball of light and which will be readily discernible by an observer for long distances and at any angle to the light.

It is another object of the invention to utilize neon tubes as the preferable light source in the marker light because of their characteristic red color, denoting danger, and because of the low power consumption of such tubes.

It is still another object of the invention to protect the gaseous discharge tubes from breakage due to wind, snow, sleet and flying objects, in such manner that the maximum light may be seen by an observer at all angles from the marker.

It is a further object of the invention to connect the gaseous discharge tubes electrically in series in an inexpensive and rugged manner and to also provide for positively so cutting out tubes which break or fail that the rest of the tubes will keep glowing.

It is a still further object of the invention to provide a cutout across the neon tubes of the unit which will have a definite time lag on overloads before cutting the tube out, which time lag will have no deleterious effect on the cutout.

It is an ancillary object of my invention to so arrange the parts of the marker light that tubes which fail or are broken may be replaced by the operator with the use of only one hand, since such lights are usually mounted at high and precarious positions.

Other objects and advantages of my invention will become apparent from the following description and drawings, wherein:

Figure 1 is a side elevational view, partially in section, of a marker light, as constructed to embody one form of my invention;

Fig. 2 is a bottom view, looking upward, of the marker light shown in Fig. 1;

Fig. 3 is a view, partly in section, and partly in side elevation, of the preferred construction of the cutout utilized by my invention;

Fig. 4 is an end view of the cutout shown in Fig. 3;

Fig. 5 is a fragmentary cross-sectional view of a spring utilized in the cutout;

Figs. 6, 7 and 8 are top, side and end views, respectively, of a contact member utilized in the cutout shown in Fig. 3; and

Fig. 9 is a side elevational view, partly in section, of a marker light, as constructed to embody another form of my invention.

In order to provide a bright red ball of light which may be seen by an observer for long distances, neon tubes are preferably utilized because of their characteristic red color when ordinary glass is utilized for the tubes and because of the low amount of power consumed by such tubes.

It is the usual practice to connect a plurality of neon tubes in series because of simplicity in wiring connections to the tubes and because reactors must be utilized with the tubes in parallel in order that the first tube of the system shall not consume the entire current. The tubes utilized in the unit are preferably so constructed that the sides thereof are substantially parallel and at a fixed distance from each other, such as a U shaped tube, such tubes have relatively great strength and the light therefrom is concentrated at their outer portions.

If no provision is made for cutting out a neon tube connected in series with other tubes when failure or breakage occurs, all the tubes will have their supply of energy cut off.

Since neon tubes normally draw a current of the order of 30 milliamperes, a film cut out is not applicable, because the current in the system is not sufficient to burn the film away immediately, and the resulting sputtering cutout delivers only a part of the energy necessary to keep the rest of the tubes glowing. Film cutouts are, furthermore, not applicable to neon tubes in series because of the momentary high starting voltage required by such tubes. Under such conditions, each time the system is started, the films are burned slightly, and will slowly deteriorate and, in time, cut out the tubes entirely, even when they are in good condition.

It is, therefore, necessary to provide a cutout which will stand high starting voltages without injury; will cut out a tube in a short time upon failure or breakage and will always allow sufficient energy to pass to ensure the glowing of the other tubes. This is important because a flashing signal may convey misleading information to an airplane pilot.

In order to provide a cutout to accomplish the aforementioned desirable results, a hollow tube, preferably of a translucent material, is provided with terminal caps on its ends so that it may be held in clips. An elongated contact member is attached, inside the tube, to one of the caps. Attached to the other cap and inside the tube, is

a spring which is held in a compressed position by being fastened, by a fusible material, to a wire, preferably also attached to the same cap as the spring.

5 When the lighting system is energized, the high starting voltage of the neon tube causes an arc to pass between the end of the spring and the contact member inside the cutout tube, but the fusible material which holds the spring compressed does not start to melt immediately because insufficient heat is generated by the low-current arc. The cutout, therefore, provides a time lag before operating because of overload. This is also an advantage when the supply voltage varies. A neon tube will drop to normal voltage a few seconds after starting, and the arcing of the cutout will stop.

If a neon tube fails or is broken, the entire line voltage will be thrown upon the cutout. Current flows through the arc set up in the cutout to the other tubes until the fusible material is melted by the heat of the arc. The spring is then released and forces itself against the elongated contact member, at which time a circuit, having low resistance, is established through the cutout.

In order that the neon tubes may be protected since the marker light is usually mounted in an exposed position, a canopy is provided which protects the tubes and also supports the conductors 30 from which the tubes receive electrical energy. The canopy and the U-shaped neon tubes are so assembled that the bottoms of the U tubes extend out farther than the edge of the canopy, so that the marker light will be plainly discernible to an observer from directly above the light. Enough neon tubes are placed in the marker light to give it the appearance of a ball of red light from a distance.

The conductors for supplying electrical energy 40 to the neon tubes are preferably solid metal brackets attached to the canopy by insulators, and each bracket is generally provided with two open tabs to receive the terminals of the tubes, each tab on one bracket receiving the terminal of a different tube. The brackets are further provided with apertured ears through which the tubes are inserted when about to be connected to the brackets. The ears support the tubes approximately in the middle thereof and decrease 45 the stresses in each tube due to its own weight, as well as external forces. The end brackets of the series connection are adjacent but not connected and are provided with only one tab and supporting ear, for reasons hereinafter explained. The 50 brackets are so disposed that the neon tubes carried thereby point angularly down to give maximum spread of light with protection for the tubes. All the brackets are provided with clips fastened thereto above the tab portions for receiving the terminal caps of the cutouts.

Since the tubes which fail or break must be usually changed in a precarious position, provision is made whereby the neon tubes may be changed by the operator with the use of only one hand. The supporting ears and the tabs on the brackets are both turned so that, when the bracket is in place, the tabs and ears point angularly downward. The neon tubes are inserted through the apertured ears until the terminals are near the open tabs. The ears are above the centers of the neon tubes and constitute pivotal points about which the tubes turn and the force of gravity therefore forces the terminals into the open tabs. The tubes may then be fastened to the 75 tabs by suitable means.

The power may be supplied from a transformer housed in a casing, preferably under the canopy, or it may be received directly from a high-voltage line through capacitors. The preferable means of connecting the system to the power supply is to utilize the canopy and the transformer casing, if a transformer is utilized, as a ground. One of the lead wires is connected to the canopy or casing and the other to the first insulated bracket. The circuit is completed from bracket to bracket through the neon tubes until the last bracket, which is also grounded to the canopy, is reached. A complete circuit is, therefore, established, with a minimum amount of wiring and a large degree of mechanical strength and adaptability.

Referring specifically to the drawings for a detailed description of the invention, numeral 1 designates each of a plurality of electrical gaseous discharge tubes, such as U-shaped neon tubes, provided with terminals 3. A canopy 5, preferably having sloping sides 7, is provided with a support 9 for fastening the entire unit to a structure to be marked. The outer periphery 11 of the canopy 5 does not extend outwardly a sufficient distance 100 to cover the neon tubes 1, when viewed from directly above. The sloping sides 7 of the canopy 5 are provided with a plurality of apertures 13 through which threaded bolts 15 on insulators 17 are inserted and fastened by turning bolt heads 105 19 to support the insulators 17 which are threaded at 23.

The insulators 17 support a plurality of brackets 21, made preferably of an electrical conducting metal, such as copper or aluminum, by means of 110 one set of the threaded bolts 15 being disposed with their heads 19 on the outside of the brackets 21 and extending into the threaded insulators 17. The brackets 21 are provided with clips 25 fastened thereto by suitable means, such as a nut-and-bolt 115 assembly 24, and are adapted to receive terminal caps 31 of the cutouts 29.

The brackets 21 are further provided with tabs 33 cut into the metal and equipped with slots 35. The tabs 33 are turned inwardly with respect to 120 the position of the brackets 21 on the canopy 5. The slots 35 are adapted to receive the terminals 3 of the neon tubes 1.

The brackets 21 are further provided with ears 37 which are also turned inwardly with respect 125 to the position of the brackets 21 on the canopy 5 and are preferably provided with resilient gaskets 39 in apertures 41 cut or stamped in the ears 37.

The ears 37 support the neon tubes 1 above 130 the middle thereof, and, as the tubes are inserted therein, the force of gravity tends to turn the terminals 3 of the tubes 1 into the slots 35 of the tabs 33, so that only one hand need be used to place the tubes in the marker light. When the 135 tubes are in place, nuts 43 fasten them to the brackets 21.

The brackets 21a and 21b at the ends of the series-connected system are provided with only one tab 33 and one ear 37, since only one terminal 140 of a tube will be held by each of these brackets. One of the end brackets 21b need not be insulated from the canopy 5, for reasons which will herein-after become apparent.

In connecting the tubes 1 to a source of electrical energy, a transformer (not shown) contained in a casing 45 may be utilized, as shown in Figs. 1 and 2. The transformer casing 45 is preferably positioned under the canopy 5 and is supported by the canopy and the supporting member 150

9. If power is to be derived directly from a high-tension line through capacitors (not shown), no transformer need be provided, and the marker light takes the form shown in Fig. 9.

5 In either case, one side of the high-tension line from the transformer or capacitor (not shown) is preferably connected directly to the canopy, and the other side of the line is connected, through conductor 47, to the supporting bracket 21a which 10 is provided with an insulator 17.

The current normally flows, through each neon tube and through the brackets 21, to the next neon tube. The last bracket 21b is grounded to the canopy, and the circuit is thereby completed.

15 Cutouts 29 are placed across the terminals 3 of each tube in order that tube failure or breakage shall not cause the uninjured tubes to stop glowing.

The cutout 29, preferably utilized in my invention, consists of a tubular member 49, preferably of a transparent material, so that the condition of the cutout may be readily ascertained, and is provided with metal terminal caps 31a and 31b on its ends to engage clips 25 on the brackets 21.

25 An elongated U-shaped conductor 51 is electrically connected to one of said caps 31a. A spring member 53 is electrically connected to the other cap 31b, and is held compressed by being fastened to the end of a wire 55, also preferably connected to the same end member 31b as the spring 53, by a fusible material 57, such as solder. The spring 53 is of sufficient length, when not compressed, to press against the elongated U-shaped conductor 51.

35 When a sufficiently high potential exists across the terminals of any of the tubes 1, an arc is set up between the end of the spring 53 and the conductor 51. If the arc persists, the heat generated thereby melts the fusible material 57 and releases the 40 spring 53. The spring 53 then presses against the elongated conductor 51, and a good electrical contact is attained between them. The tube across which the cutout thus operating is positioned is automatically cut out of the circuit, while the rest 45 of the tubes receive energy and, therefore, glow.

It will be noted that a certain time delay is present before the fusible material is melted and the cutout operates. During the time interval, however, current is flowing to the other tubes through 50 the arc between the spring and the elongated member. It is also apparent that the high starting voltage for a few seconds of the tube will not harm the cutouts, nor will temporary variations in supply voltage, because of the time lag.

55 It is apparent that I have provided an obstruction marker light which gives the appearance of a ball of light when observed, and that some light is emitted as long as one tube is not broken or otherwise fails. I have also provided protection for the fragile discharge tubes and combined therewith an inexpensive and rugged system of supplying power to the tubes. The system itself is inexpensive to operate, and ease of maintenance is ensured by designing the unit 60 so that repairs may be made thereon with one hand in precarious positions. I have further provided a cutout which is positive in action and easy to replace.

Although I have shown and described a specific embodiment of my invention, it is apparent that modifications and changes may be made therein without departing from the spirit and scope of the appended claims.

I claim as my invention:

75 1. An obstruction marker light comprising a

plurality of light sources, a two-wire source of electrical energy, means for connecting said light sources in series to the source of electrical energy, an electricity-conducting protecting canopy provided with a plurality of insulators, said connecting means including supports for said light sources, all but one of said connecting means being supported by said insulators, one side of said source of electrical energy being grounded to said conducting canopy, and one of said connecting means being grounded to said canopy, the other side of said source of energy being connected to one of said connecting means to complete the series circuit from the light sources to the energy source.

2. An obstruction marker light comprising a plurality of light sources, a two-wire source of electrical energy, means for connecting said light sources in series to the source of electrical energy, an electricity-conducting protecting canopy provided with a plurality of insulators, said connecting means including supports for said light sources, all but one connecting means being supported by said insulators one side of said source of electrical energy being grounded to said conducting canopy, and one of said connecting means being grounded to said canopy, the other side of said source of energy being connected to one of said connecting means to complete the series circuit from the light sources to the energy source, each light source being provided with means for removing it from the circuit when excessively high current is present.

3. An obstruction marker light comprising a plurality of elongated tubular light sources, a source of electrical energy, means for connecting said light sources to the source of electrical energy, a protecting canopy for said light sources provided with a plurality of insulators, all but one connecting means being supported by said insulators, said connecting means comprising a bracket of conducting material provided with at least one punched-out tab for terminals for said light sources, and being further provided with at least one turned ear which is apertured for supporting said light sources.

4. An obstruction marker light comprising a plurality of elongated tubular light sources, a source of electrical energy, means for connecting said light sources to the source of electrical energy, a protecting canopy for said light sources provided with a plurality of insulators, all but one connecting means being supported by said insulators, said connecting means comprising a bracket of conducting material provided with at least one punched-out tab for terminals for said light sources, and being further provided with at least one turned ear which is apertured for supporting said light sources, said tabs and ears being constructed to point substantially downward when said marker is in its upright operative position.

5. A marker light comprising, in combination, a support member, a transformer case carried by the support member, a metallic canopy member secured to the transformer case, a transformer mounted in the case having a primary winding for connection to a source of electrical energy and a secondary winding one terminal of which is connected to the canopy member, and a plurality of substantially equally spaced, radially extending gaseous discharge tubes connected in series-circuit relation supported by and insulated from the canopy member having one terminal of the series circuit connected to a second ter-

minal of the secondary winding and the other terminal connected to the canopy member.

6. A marker light comprising, in combination, support means including a main body member, a plurality of radially extending series circuit connected gaseous discharge tubes supported by and insulated from the support means in substantially equally spaced relationship, one terminal of the series circuit being connected to the support means, and means for connecting the remaining terminal of the series circuit and the support means to a source of electrical energy.

7. A marker light comprising, in combination, support means including a main body member,

a plurality of substantially equally spaced support brackets secured to and insulated from the support means, each of said support brackets being provided with a plurality of upturned apertured portions and a plurality of upturned notched portions, a plurality of gaseous discharge tubes provided with terminals having reduced portions, said tubes being disposed to be mounted within said apertured portions with the reduced portions of the terminals engaging the notched portions, means for securing said tubes in operative position, and means for connecting the discharge tubes to a source of electrical energy.

RALPH E. MARBURY. 90
